DESIGN.

J. A. JOHNSON.

VEHICLE TOP.

APPLICATION FILED APR. 15, 1916.

49,803.

Patented Oct. 24, 1916.

John August Johnson Inventor
By his Attorney
Frank D. Lent

UNITED STATES PATENT OFFICE.

JOHN AUGUST JOHNSON, OF BROOKLYN, NEW YORK, ASSIGNOR TO P. & L. COMFORT BABY CARRIAGE CO. INC., OF BROOKLYN, NEW YORK, A CORPORATION OF NEW YORK.

DESIGN FOR A VEHICLE-TOP.

49,803.

Specification for Design.

Patented Oct. 24, 1916.

Application filed April 15, 1916. Serial No. 91,487. Term of patent 7 years.

To all whom it may concern:

Be it known that I, JOHN AUGUST JOHNSON, a citizen of the United States, residing at Brooklyn, in the county of Kings and State of New York, have invented a new, original, and ornamental Design for Vehicle-Tops, of which the following is a specification, reference being had to the accompanying drawing, forming part thereof.

In the drawing, the figure is a perspective of a vehicle top embodying my invention.

I claim:

The ornamental design for a vehicle top, as shown.

JOHN AUGUST JOHNSON.

Witnesses:

ARTHUR T. WEYGANDT,
HELEN V. FITZPATRICK.
